US00D851772S

(12) **United States Design Patent** (10) **Patent No.:** **US D851,772 S**
(45) **Date of Patent:** **** Jun. 18, 2019**

(54) **SURGICAL DRAPE**

(71) Applicant: **Medline Industries, Inc.**, Mundelein, IL (US)

(72) Inventors: **Kimberly Haines**, Deerfield, IL (US);
Robert Allen Lockwood, Libertyville, IL (US); **Francis A Czajka**, Libertyville, IL (US)

(73) Assignee: **Medline Industries, Inc.**, Northfield, IL (US)

(**) Term: **15 Years**

(21) Appl. No.: **29/577,807**

(22) Filed: **Sep. 15, 2016**

Related U.S. Application Data

(60) Continuation of application No. 29/360,169, filed on Apr. 21, 2010, now abandoned, and a continuation of application No. 13/761,896, filed on Feb. 7, 2013, now Pat. No. 9,636,180, which is a continuation of application No. 12/985,076, filed on Jan. 5, 2011, now Pat. No. 8,371,306, which is a division of application No. 12/008,818, filed on Jan. 14, 2008, now Pat. No. 7,886,742, said application No. 29/360,167 is a continuation of application No. 12/008,818.

CLAIM

The ornamental design for a surgical drape, as shown and described.

DESCRIPTION

The sole FIGURE is a top, plan view of a surgical drape showing our new design.

The broken lines shown in the sole FIGURE are included for the purpose of illustrating environmental elements only and form no part of the claimed design.

In the drawings, the rectangular cover element is made of a material that has no appreciable thickness. The octagonal

(Continued)

shape and indicia "stop" are ornamental decorations of an item attached to a fenestration cover attached to the surgical drape.
